UNITED STATES PATENT OFFICE

LEGGETT C. CAMPBELL, OF NEWARK, NEW JERSEY, ASSIGNOR TO NEWARK WIRE CLOTH COMPANY, OF NEWARK, NEW JERSEY, A CORPORATION OF NEW JERSEY

WIRE CLOTH SELVAGE

Application filed September 21, 1929. Serial No. 394,324.

This invention relates to metallic wire cloth selvages and is particularly applicable to wire cloth for use in screen grids for radio tubes. Such grids are made of comparatively narrow cloth. To make selvages on the edges of such narrow cloth by weaving methods increases the cost thereof unnecessarily. Furthermore, it is quite difficult and expensive to use present machines for the weaving of cloth of such narrow widths with woven selvages thereon. Some means, however, should be used for preventing the cloth from unraveling.

My invention contemplates the production of such an edge on the cloth as forms a satisfactory and efficient selvage preventing the cloth from unraveling without the necessity for weaving or otherwise manipulating the wires of the cloth, and such as can be inexpensively made simultaneously with the cutting of the cloth to the desired width. The various objects of my invention will be clear from the description which follows, and from the drawings, in which

25 Fig. 1 is an elevational view on a greatly enlarged scale of a piece of metallic wire cloth showing my improved selvage thereon.

Fig. 2 is a sectional view of the same, and

30 Fig. 3 is a view similar to Fig. 1, of the partly severed and selvaged cloth.

In that practical embodiment of my invention which I have illustrated by way of example, the cloth may consist of warp wires 10 and weft wires 11, said wires being inter-

35 woven in the customary manner as is well known in the art, to provide a cloth opening 12, shown as slightly greater than the diameter of the wires.

It will be understood that the dimensions 40 of the drawings have been greatly exaggerated for clarity, and that in practice, the wire openings and diameters are usually measured in thousands of an inch. As an example of the dimensions which I have 45 found convenient for cloths on which my new selvage may be made, the wires may be about .007 of an inch in diameter, and the cloth opening 12 may be .0097 of an inch square, though it will be understood that I do not 50 intend to limit myself to these dimensions, as

my invention may be applied to cloths of many different dimensions. At the edge of the piece of cloth, I provide my improved selvage indicated generally by the numeral 13 which when viewed by the naked eye, presents the appearance of a completely closed or sealed edge. Said selvage is quickly, easily and inexpensively formed automatically when the cloth is severed to the desired width by my improved method, as is fully 55 pointed out in my copending application for patent for machine for and method of making selvages for wire cloth, Serial No. 394,325, filed September 21st, 1929.

As indicated in Fig. 3, the cloth may be 60 woven in any width which may be found convenient and economical in the operation of the cloth weaving machines. In order, however, to provide a comparatively narrow strip of such cloth, of uniform width throughout, 65 such as for instance, is of the proper width for use in radio tube screen grids, the cloth is severed by means of a suitable tool which severs the weft wires 11 and simultaneously bends and points said wires to form the selvage 13. The tool 14 which I prefer to use for this purpose is indicated diagrammatically in Fig. 3. The thickness of the tool, however, is shown on a greatly exaggerated scale in order to indicate the severing operation 70 with greater clarity. Said tool being fully shown and described in my said copending application, Serial No. 394,325, it need not be 75 here shown or described in detail.

Suffice it to say that in order to cut the 80 cloth and to simultaneously form the selvage thereon, the tool is pushed between adjacent warp wires 10 and moved through the cloth, or the cloth is pulled against the tool, the edge of which remains at all times about half 85 way between a pair of the warp wires.

After the cutting and bending operation 90 has been completed, it will be seen that the ends 15a and 15b of adjacent weft wires 11 lie substantially on opposite sides of the edge 95 warp wire 16. For example, the bent ends 15a of alternate weft wires, as illustrated in Figs. 2 and 3, are arranged substantially nearer the rear face of the cloth, while the ends 15b of the other weft wires are nearer 100

the front face of the cloth. Furthermore, the edge warp wire 16 is arranged nearer its adjacent warp wire 17 than the normal distance between the warp wires, that is, a distance less than the cloth opening 12. The 5 edge warp wire, by reason of this arrangement, usually produces an edge cloth opening 20 of about half the width of the normal cloth opening 12.

10 In the finished selvage, the end portions 15a and 15b of the weft wires 10 may be of slightly greater length than one and one-half times the normal distance between adjacent warp wires for the reason that said end 15 portions may be slightly stretched during the cutting operation. It will be seen, therefore, that said ends project beyond the edge warp wire 16 a distance less than the normal distance between warp wires 10. Said ends 20 15a and 15b, furthermore, due to the cutting operation, terminate in more or less flat surfaces such as 18, substantially parallel to the axes of the warp wires 10, 16 and 17 and thereby forming a point as 19 on each of the 25 end portions of the weft wires.

It will be understood, however, that due to the microscopic dimensions of said points 19, the points may be somewhat dull due to the dropping off of the extreme ends of said 30 points in the form of dust during the cutting operation, and therefore, I do not intend to be understood as limiting myself to the formation of perfect points at the ends of the bent portions of the weft wires.

35 All of the bends 15a and 15b are bent in the same direction and each bend is preferably turned through an angle of approximately 90° so that the point 19 of one bent end 15a lies quite close to and may possibly, 40 though not usually, touch the bent end 15b of the nearest succeeding parallel weft wire. However, even though the point does not so touch the next bend, it lies so close to said bend that the edge of the cloth at the selvage 45 appears substantially closed or sealed. This appearance and structure is aided by the fact that the bent portions 15a and 15b lie closer to each other than do the weft or warp wires, owing to the formation of said bends.

50 While the bent portions 15a and 15b may extend through an angle slightly less than 90°, or equal thereto, or slightly greater than 90°, said bend usually extends through an angle in all cases less than 180°, the bends 55 being all of substantially the same curvature, and all being single bends as distinguished from double bends, or bends along reverse curves. Said bends may begin at the warp wire 17 or slightly thereabove, depending 60 largely on the manner in which the tool cuts the weft wires.

In other words, the bent end portions 15a and 15b are all of substantially the same curvature and all point substantially in the 65 same direction, all being bent away from

the axis of the corresponding weft wire toward the next succeeding weft wire.

It will be seen that the edge warp wire 16 cannot move outwardly toward the edge of the cloth since it is prevented from doing so by the bends 15a and 15b and cannot pass through the practically closed space therebetween, nor can said edge warp wire move towards its adjacent wire 17 owing to the interweaving thereof in the usual manner 75 with the weft wires. It will also be seen that for the same reason, the weft wires 11 cannot move relatively even though the ends thereof are free and independent of each other so that unraveling of the cloth is 80 prevented by my improved selvage.

It will be seen that I have provided a simple, inexpensive and efficient selvage for narrow widths of wire cloth, well adapted to meet the severe requirements of practical 85 use.

It will be understood that while I have shown and described a preferred embodiment of my invention, I do not wish to be understood as limiting myself thereto but, 90 intend to claim my invention as broadly as may be permitted by the state of the prior art and the terms of the appended claims.

I claim:

1. In a wire fabric comprising interwoven warp wires and weft wires, a selvage comprising an unmutilated edge warp wire spaced from the adjacent warp wire a distance less than the normal distance between said warp wires, and a terminal bent end on each weft wire extending slightly above said edge warp wire and bent through an angle of approximately 90° toward the adjacent weft wire and pointed, said bent ends having a single curvature only and all extending in the same direction. 100

2. In a woven wire fabric having a set of interwoven warp wires substantially parallel to each other and a set of weft wires substantially parallel to each other and arranged at substantially right angles to the warp wires, a selvage including an end on each of a parallel set of wires bent substantially in the plane of the face of said cloth, and out of the line of the axis of the wire in a curve directed towards the next succeeding parallel wire, said end being pointed and substantially free of the adjacent parallel wire. 110

3. In a woven wire fabric including a set of substantially parallel wires, a selvage formed by bending the ends of said wires in the same direction substantially in the plane of the face of the cloth, each bent end terminating in advance of and being free of the next succeeding parallel wire but sufficiently close thereto to form a substantially closed edge on the cloth. 120

4. In a woven wire fabric including a set of substantially parallel wires, a bent end 130

on each of said wires forming a selvage for said fabric, said end being curved toward the next adjacent parallel wire along a line of single curvature but being self-maintained free and independent of said adjacent wire and terminating at a point in advance of said adjacent wire and of the curved end thereof.

5. In a woven wire fabric including a set 10 of substantially parallel wires, a bent end portion on each of said wires curved through an angle not greater than 90° toward the next succeeding parallel wire, said end portion terminating in a substantially flat surface 15 face arranged substantially at right angles to the axis of the remainder of said wire to form a point on said end.

6. In a woven wire fabric having a substantially parallel set of warp wires and another parallel set of weft wires arranged substantially at right angles to the warp wires, a selvage comprising an edge warp wire spaced from its adjacent warp wire a distance less than the distance between the 25 remaining warp wires, and substantially independent bent ends on said weft wire maintaining said edge warp wire and said weft wires in place against unraveling.

7. In a woven wire cloth fabric, a selvage 30 comprising an edge warp wire spaced from its adjacent warp wire a distance less than the cloth opening, weft wires extending past said edge warp wire, and ends on said weft wires all bent in the same direction and substantially free and independent of each other for maintaining said edge warp wires and said weft wires in place, the alternate 35 ends of said weft wires being arranged on one side of said edge warp wire corresponding to one face of the cloth and the other alternate ends being arranged on the other side of said edge warp wire corresponding to the other face of the cloth.

8. In a woven wire fabric, an edge warp 45 wire and weft wires projecting beyond said warp wire a distance less than the cloth opening, the end of each of said weft wires beginning at the second warp wire from the edge of the fabric, being bent toward the bent 50 end of the next succeeding weft wire.

9. In a woven wire cloth fabric, a set of substantially parallel wires and ends on said wires of less length than twice the cloth opening, each of said ends having a single bend 55 terminating close to the bent end of the succeeding parallel wire and extending through an angle of less than 180° to form a substantially closed selvage.

10. A selvage for a woven wire fabric comprising an edge warp wire spaced from its adjacent warp wire a distance less than the normal cloth openings, and bent portions on the ends of the weft wires, the bends of said bent portions beginning at a point below said 65 warp wire and subtending an angle of ap-

proximately 90° and each terminating in advance of the succeeding bent portion.

11. A selvage for a woven wire cloth fabric comprising an edge warp wire spaced from its adjacent warp wire a distance less than 70 the remaining cloth openings, and ends on the weft wires bent substantially in the plane of the face of the cloth and all extending in the same direction but self-maintained out of engagement with each other.

12. A selvage for a woven wire cloth fabric comprising an edge warp wire parallel to the remaining warp wires but spaced therefrom a distance less than the normal spacing between warp wires, a bent end on each weft wire, said ends being substantially parallel to each other and each of said ends terminating beyond the edge warp wire in advance of the succeeding bend toward which it is directed.

13. A selvage for a woven wire cloth fabric comprising an edge warp wire spaced from its adjacent warp wire a distance less than the cloth opening, and free ends on the weft wires all bent in the same direction and extending beyond said edge warp wire toward the edge of the cloth and terminating at the extreme edge of the cloth substantially to close said edge.

14. A selvage for a woven wire cloth fabric 95 comprising a series of substantially parallel wires and free end portions on said wires each bent along a line of single curvature substantially in the plane of the face of the cloth through an angle of approximately 90° and terminating at the extreme edge of the cloth 100 to form said edge.

15. A selvage for a woven wire cloth fabric comprising a series of substantially parallel wires, an edge wire arranged at right angles to said parallel wires, and spaced bent ends on said parallel wires, the adjacent ones of said ends lying on opposite sides of said edge wire, said ends being of similar shape and each curved along a line of single curvature and terminating beyond said edge wire and at the extreme edge of the cloth and substantially closing the edge of the cloth.

16. A selvage for a woven wire cloth fabric comprising pointed and bent end portions of a set of parallel wires, said end portions all extending in the same direction and terminating at the extreme edge of the cloth, and said end portions being substantially parallel and spaced apart through the greater portion of their length a distance less than the normal cloth opening for substantially closing the edge of the cloth.
